WATCHCASE

Max Schechmer, Flushing, N. Y.

Application January 28, 1941, Serial No. 376,261

3 Claims. (Cl. 58—90)

My invention relates to watches of the class known as "waterproof."

In such watches the greatest difficulty is encountered in preventing the ingress of water, dust or moisture through the necessary opening which must be provided for the watch stem which must be rotatable to wind the watch and movable longitudinally to set the hands of the watch.

Among the means at present and in most general use is a packing usually a sleeve of rubber which is provided to surround the stem. These sleeves, however, in a comparatively short time become worn or oxidized so that they no longer tightly engage the stem and its aperture, with the result that the packing fails of its purpose.

Another method is a rather elaborate spring mechanism enclosed in the crown. The springs thus employed break and the device then becomes inoperative.

My invention has for its principal object to render the watch impervious to water, dust and moisture without employing any packing of any sort whatsoever.

A further object is to provide a construction for that purpose without employing springs of any form.

A further object is to provide a construction which, in a simple and inexpensive manner, will permit both winding and setting the watch in the usual manner.

A further object is to attain these objects without the necessity of employing gaskets, or any parts formed of expendable material.

Another difficulty encountered in watches generally is that the stem being, of very small diameter, is easily broken when subjected to a shock at the crown.

Further object of my invention is to provide a construction which will protect the stem of a watch against breakage due to sudden shock by employing an auxiliary stem of larger diameter at the aperture into the watch case.

My means of accomplishing the foregoing objects may be fully comprehended by having reference to the accompanying drawing, which is hereunto annexed and is a part of this specification in which similar reference numerals refer to similar parts throughout.

Fig. 1 is a fragmentary elevational view showing my device applied to the watch case;

Fig. 2 is a cross-sectional view showing my device in inoperative position;

Fig. 3 is a view similar to Fig. 2, but showing 55

my device in operative position for the resetting and winding of the watch;

Fig. 4 is a cross-section taken on the line 4—4 of Fig. 3;

5 Fig. 5 is an exploded detail view of the parts which go to make up my device; and

Fig. 6 is a modification of my device.

In the drawing I have shown only a fragmentary portion of the watch case 10 as it is of 10 the conventional design which is well known to the industry.

In the periphery of the case 10 is mounted a bushing 11, which is provided with internal threads 12 to which is fitted the external threads 15 14 on a reduced portion 15 of a tubular sleeve 16. The reduced portion forms a shoulder 17 which is adapted to abut the bushing 11 and form a tight joint.

The upper end of the tubular sleeve 16 is 20 closed by a crown 13, of standard construction which is preferably secured to the sleeve by solder or by sweating or in any other suitable or desired manner in order to effect a seal which will be impervious to water, dust or moisture.

25 The periphery of the crown is provided with the conventional knurling for convenient manipulation such as is required for winding or setting the watch.

Within the tubular sleeve 16 I mount an auxiliary stem 18 which is longitudinally slidable therein.

30 This auxiliary stem 18 is provided with a head 19 as clearly seen in Fig. 5 from the lower surface of which projects pins 20 and 22 which are 35 fitted to and adapted to engage corresponding recesses 24 and 26 which are drilled, cast or otherwise formed in an internal shoulder 27 formed on the inside of the tubular sleeve 16.

This sleeve has its lower portion 15 provided 40 with a central axial opening 28 to which is fitted the auxiliary stem 18. The opening 28 serves to center and also acts as a guide for the auxiliary stem 18. The upper portion of the tubular sleeve 16 is bored out to fit the head 19 of the auxiliary stem 18. The end 29 of the auxiliary stem 18 is provided with internal threads 30 which fit the stem of a standard watch. This is not shown nor is it deemed necessary to describe it or its operation in detail since its construction and operation are well known to persons skilled in the art.

45 The operation of my improvement is as follows:

The crown 13 is rotated in a counter-clockwise direction to unscrew the tubular sleeve 16 from

the bushing 11. When it is free as seen in Fig. 3, the sleeve is then drawn outwardly until the pins 20 and 22 engage the recesses 24 and 26 at which point rotation of the crown in clockwise direction will carry with it the auxiliary stem and in turn the watch stem (not shown) and the watch will be wound.

Further withdrawal will cause the watch stem to be disengaged from the winding position and move it to the setting position and the hands of the watch may be moved to the correct position.

This actuation of the parts being those of the standard watch movements, they will be clearly understood by those persons engaged in the industry.

Obviously, the reverse movement will free the pins 20 and 22 from the recesses 24 and 26 and the tubular sleeve can be screwed tightly in place thus rendering the watch impervious to water, dust or moisture.

From the foregoing it will be seen that I have been able to construct a water, dust or moisture proof watch without having to employ any sleeves of expendable material or any springs which are liable to be broken in use.

In Fig. 6 I show a slightly modified construction of the bushing. As shown in this view the bushing is provided with an extension 32 which is provided with external threads 34. The tubular sleeve 16 in this form is provided with internal threads 36 which fit the threads 32. Otherwise the construction is the same and the operation is identical. The foregoing description and drawing is furnished solely for illustration purposes and not in any manner as a limitation upon my invention, and I do not intend to be limited to the specific details shown and described except as such limitations appear in the hereinafter contained claims.

Having described my invention, what I regard as new and desire to secure by Letters Patent is:

1. In a watch having a stem and an aperture in its periphery for said stem; a bushing mounted in said aperture, threads on said bushing, a tu-

5 bular sleeve which is adapted to be threaded on said bushing and seal the same, a crown fixedly mounted on the outer end of said tubular sleeve, an internal shoulder in said sleeve, there being recesses in said shoulder and an auxiliary stem adapted to engage the stem of the watch, said stem being mounted in said sleeve and longitudinally slidably therein, a head on said stem and pins on the lower side of said head which engage said recesses.

2. In a watch having a stem and an aperture in its periphery for said stem; an internal bushing fixedly mounted in said aperture, a tubular sleeve having external threads which fit the threads in said bushing, an external shoulder on said sleeve which abuts said bushing forming a sealed joint, a crown which closes the upper end of said tubular sleeve and which is hermetically attached thereto, an internal shoulder in said tubular sleeve, said shoulder having recesses, an auxiliary stem adapted to engage the stem of the watch, said auxiliary stem being mounted in said tubular sleeve, there being a recess in said shoulder, a head on said auxiliary stem, pins on the lower side of said head formed integral therewith, adapted to engage the recesses in the shoulder on the tubular sleeve.

3. In a watch having a stem and an aperture in its periphery for said stem; an internal bushing mounted in said aperture, a tubular sleeve, external threads thereon which fit the threads in said bushing, an external shoulder on said sleeve which abuts said bushing forming a sealed joint a crown on the upper end of said tubular sleeve and which is hermetically attached thereto, an internal shoulder in said tubular sleeve, said shoulder having recesses therein, an auxiliary stem adapted to engage the stem of the watch, said auxiliary stem being mounted in said tubular sleeve, there being recesses in said shoulder, a head on said auxiliary stem, pins on the lower side of said head formed integral therewith, adapted to engage the recesses in the shoulder on the tubular sleeve.

MAX SCHECHMER.
